VALVE TOOL

Frank Akin, Dallas, Tex.

Application October 13, 1947, Serial No. 779,575

4 Claims. (Cl. 29—217)

1

This invention relates to automobile repairing tools and equipment and more particularly to a tool for installing and extracting poppet valves in internal combustion engines.

The principal object of the invention is to provide a tool for installing and removing valves which consists of a frame in which is mounted a valve engaging cross-head capable of longitudinal movement in the frame by means of a screw rod, to lift the valve against the resistance of its spring, the latter being held by the valve retaining clip. The invention further aims to provide removable valve guide engaging fingers supported by a mounting plate freely movable in the frame on the screw rod, on which latter is threaded a nut for urging the plate downwardly to exert pressure on the valve guide to relieve pressure of the valve spring on the retaining clip to effect release of the latter and removal of the valve.

Another object of the invention is to provide a valve tool whose novel and simple construction makes possible the extraction and installation of a valve in considerably less time than was heretofore possible with conventional tools designed for the purpose and one which requires no special skill for its manipulation.

With the foregoing objects in view, the invention has further reference to certain features of accomplishment which will become apparent as the description proceeds, taken in connection with the accompanying drawing wherein:

Figure 1 is a fragmentary sectional view of an internal combustion engine showing the invention in the preliminary operation of lifting a valve.

Figure 2 is a similar view showing the valve in raised position preparatory to displacing the valve guide.

Figure 3 is yet another position of the tool, showing the valve spring collapsed to relieve pressure on the valve retainer to permit its removal and extraction of the valve, and

Figure 4 is a side elevational view of the invention per se.

Continuing with a more detailed description of the drawing, reference is primarily made to Figure 4 wherein numeral 10 denotes a substantially inverted U-shaped frame having longitudinal slots 11 in each leg thereof which open at the bottom thereof but terminate short of the top of the frame. Extending freely through an aperture 12 in the top of the frame 10 is a threaded rod 13 having head 14 at its top and a cross-head 15 non-rotatably mounted by means

2

of a pin *a* on its lower end. The ends of the cross-head 15 are of less width than the body thereof and are slidably received in the slots 11 of the frame 10, hence the cross-head is restrained from rotating in the frame.

The cross-head 15 has a cavity in its underside defining claws or hooks 16 of wedge shape which are adapted to engage under the edges of the head 17 of a poppet valve, as shown in Figures 1 to 3 inclusive.

Freely mounted on the screw rod 13 within the frame 10 is a plate 18 having at each end an aperture *b* (Fig. 4). A pair of fingers 19 are provided, one being disposed in each open side 15 of the frame 10, each having a pin 20 receivable in an aperture *b* of the plate 18 but removable therefrom. A screw 21 is threaded into each finger 19 to serve as a handle for better manipulation of the fingers.

20 Each of the fingers 19 is bent at 22 intermediate its ends to dispose its lower end well inwardly of the end of the mounting plate 18 for the purpose to be presently described.

In order that the operation of the invention 25 may be more fully understood, a part of an engine block 23 is shown in Figures 1 to 3 which illustrate also progressive steps employed to extract a valve. The valve 17 is conventional, as is likewise the valve spring 24, guide 25 and retainers 26. Normally, the valve is actuated under the tension of the spring 24 by the cam shaft 27 and cam follower 28, the upper end of the spring bearing against the valve guide 25 and which latter, in turn, is held against upward displacement by the upper retainer 26. The pressure exerted by the spring 24 is such that without some medium for contracting the spring, the upper retainer 26 cannot be withdrawn from the slot of the valve guide in which it reposes.

The frame 10 of the invention is set on the block 23 in the manner shown and the crank shaft of the engine is manually turned until the head of the valve to be extracted is lifted 30 from its seat. It is now possible to slide the frame 10 sideways so that the valve head will be received in the cavity of the cross-head 15 whereby the opposed hooks 16 will engage thereunder. During this operation, it is preferred that the fingers 19 be left off the tool.

After having set up the tool in the manner described, a wrench is applied to a nut 29 on the screw rod 13 and this nut is rotated to advance the same against the top of the frame 35 10. This operation raises the screw rod 13 and

with it the cross-head 15, thereby lifting the valve 17 further from its seat against the resistance of its spring 24. The guide 25 however remains in place due to the presence of the upper retainer 26.

After the valve has been lifted a predetermined distance, the fingers 19 are installed in the manner described and shown, with their lower ends resting on the top of the guide 25. A wrench is then applied to a nut 30 threaded on the screw rod 13 within the frame 10. This nut is brought to bear on the top of the plate 18, causing the same to move downward, urging the fingers 19 against the valve guide 25 and further collapsing the valve spring 24. This latter operation is disclosed in Figure 3 and shows the upper retainer 26 retracted and relieved of the pressure of the spring 24 so that it may easily be withdrawn from the annular groove in the guide 25 in which it is held.

After the retainer 26 has been removed from the guide 25, the valve assembly may be lifted from the block, after which the nut 30 is backed up to relax the spring 24 so that the fingers 19 can be removed. When this is done, the valve assembly will be released from the tool.

To install a valve assembly, it is necessary to employ a tool, which is of conventional manufacture, to compress the spring 24 in order that the fingers 19 may be set against the top of the valve guide 25. First, however, the valve head is disposed in the cavity of the cross-head 15. The fingers 19 will hold the spring 24 collapsed to allow sufficient spacing between the valve head and guide that the upper retainer 26 may be inserted into the groove of the guide after the valve assembly has been inserted into the motor block 23. When the retainer 26 is in place, the nut 30 is backed up to relax the spring 24 so that the fingers 19 may be removed, after which the cross-head 15 is slid from the valve 17.

Manifestly, the construction as shown and described is capable of some modification and such modification as may be construed to fall within the scope and meaning of the appended claims is also considered to be within the spirit and intent of the invention.

What is claimed is:

1. A valve gripping tool including an inverted U-shaped frame, a screw rod mounted in said frame adapted to transmit axial thrust, a cross-head mounted in said frame and carried by the lower end of said screw rod and constrained by said frame against other than longitudinal displacement on said screw rod, said cross-head having confronting wedge shaped hooks for engaging underneath the head of a valve, a plate freely mounted on said screw rod above said cross-head, a pair of fingers removably attached at their upper ends to the ends of said plate and whose lower ends are disposed inwardly of the ends of said plate and adapted to bear against the guide on the stem of said valve, a nut on said screw rod adapted to bear against said frame to raise said screw rod and said cross-head, a second nut on said screw rod movable against said plate to effect downward displacement of said fingers, and means carried by each of said fingers for independently manipulating the same.

2. A valve gripping tool including an inverted U-shaped frame, a screw rod freely movable longitudinally therein adapted to transmit axial thrust, a cross-head carried by said screw rod and held by said frame against other than longitudinal displacement on said screw rod, confronting wedge-shaped hooks formed on the underside of said cross-head adapted to receive a valve head, a nut on said screw rod adapted to be advanced against the top of said frame to raise said cross-head, a valve guide engaging finger on each side of said cross-head, and a mounting plate freely mounted on said screw rod above said cross-head to which said fingers are releasably attached and means on said screw rod adapted to be advanced against said plate to effect downward movement of said fingers against said valve guide.

3. In a valve gripping tool, a frame, a screw rod freely movable longitudinally in said frame, a cross-head carried by said rod, a pair of confronting, wedge-shaped hooks formed on the underside of said cross-head and adapted to engage under the head of a valve, a nut threaded on said screw rod and movable against the top of said frame to effect upward displacement of said cross-head, a valve guide engaging finger on each side of said cross-head, the lower portion of said fingers being turned inwardly towards 30 and into parallelism with said screw rod, a plate mounted freely on said screw rod above said cross-head for suspending said fingers and means threaded on said screw rod adapted to be advanced against said plate to move said fingers into 35 engagement with said valve guide.

4. In a valve gripping tool, a frame, a screw rod extending freely through said frame, a cross-head mounted on said screw rod and held by said frame against other than longitudinal displacement in said frame, a pair of opposed, wedge-shaped hooks carried by said cross-head adapted to engage the head of a valve, a nut threaded on said screw rod and movable against said frame to raise said cross-head, a finger on each side of said cross-head, said fingers being adapted to engage the top of the guide of said valve, means on said screw rod above said cross-head for supporting said fingers and means threaded on said screw rod and movable against 50 said finger supporting means to urge said fingers operatively against said valve guide.
